UNITED STATES PATENT OFFICE.

WILLIAM G. PANCOAST, OF WILMETTE, ILLINOIS.

LIFTING JACK.

Application filed July 23, 1923. Serial No. 653,078.

To all whom it may concern:

Be it known that I, WILLIAM G. PANCOAST, a citizen of the United States, and a resident of Wilmette, in the county of Cook and State of Illinois, have invented certain new and useful Improvements in Lifting Jacks, of which the following is a specification.

This invention relates to improvements in lifting jacks, and more particularly to portable devices commonly used in connection with automobiles for making repairs, and especially for lifting the wheels from the ground in order to replace or change tires.

Referring particularly to that type of jack extensively used for automobile repair work, the same is designed to be placed on the ground directly beneath the axle, spring, or other substantial portion of the frame, and then operated to bring the upper end into engagement with the vehicle. The operation of jacks in this manner is attended with some degree of danger, since there is the possibility of an insecure supporting contact between the vehicle and the jack and the liability of injury to persons, should the jack slip and the vehicle suddenly be lowered to the ground. Furthermore, in placing the jack in proper lifting position it is frequently difficult to do so properly without virtually crawling beneath the vehicle, particularly at the rear end thereof, where spare tires, bumpers, and other accessories extend some distance beyond the body.

It is therefore the object of the present invention to overcome the disadvantages and eliminate the dangers hereinbefore enumerated, as well as to provide a new and useful lifting device embodying other features calculated to provide a more efficient and practical tool.

In the accompanying drawing a preferred construction for the improved jack is illustrated, wherein

Figure 1 is a view partially in end elevation and partially in vertical section of the device,

Figure 2 is a view in vertical section taken on line 2, 2 of Figure 1,

Figure 3 is a cross-sectional view taken on line 3, 3 of Figure 1, and

Figure 4 is a cross-sectional view taken on line 4, 4 of Figure 2.

The preferred form of jack disclosed comprises two main elements common to devices of this character, namely, an upright stand

or pedestal designed to rest upon the ground, and having a base or foot plate, and a vertically extensible shank. Various methods have been adopted for operating the jack by extending or retracting the movable shank, the common forms being the ratchet type and the screw type, the former involving the pumping action of a lever to lift the vehicle, and the latter the rotation of a rod or shaft. Although either, or any suitable type of lifting mechanism may be employed, I prefer to disclose the so-called "screw-jack" type, since it permits the use of a long operating handle which may be manipulated at a distance from the point of application of the jack itself.

Following the general combination of parts before included in such a device, the pedestal 1 comprises two main parts, namely, an internal and relatively stationary post 2, and an external rotative sleeve 3. The post 2 has formed integral with its lower end a base or foot plate 4 designed to afford a substantial footing or support for the device. As clearly shown in Figure 2, the post 2 extends upwardly from the center of its base plate 4, and is split or bifurcated from its top to bottom, thus forming two parts or halves with a slot or opening therebetween, in which is mounted for vertical sliding movement, the extensible shank 5. As clearly shown in Figure 4, the shank 5 resembles somewhat an I-beam section, being slightly reduced in width throughout its central portion, thus providing interfitting guideways (as at 6) between the moving parts. The sleeve 3 surrounds the post 2, the outer faces of the latter being curvilinear to conform to the internal circumference of the sleeve. This sleeve is rotative and is supported at its lower end upon a roller step bearing 7 sunk in an annular raceway 8 formed in the upper face of the base plate 4 at the lower end of the post 2. A flange or radial enlargement 3^a is formed at the lower end of the sleeve which partially rides in the raceway 8, thus centering the sleeve in its rotative movement.

The internal surface of the sleeve is tapped from end to end with square helical screw threads of comparatively large pitch which mesh with a threaded portion 5^a at the lower end of the shank 5, the threads being of the same formation and pitch as those of the sleeve 3. As clearly shown in Figure 4, the threads of the shank 5 are

formed along the opposite sides thereof, and project into engagement with the complementary threads of the sleeve.

The upper end of the sleeve 3 terminates 5 below the end of the post 2, which it surrounds, thereby allowing for the mounting of a cap member 9 in screw threaded connection with said post. The cap member is provided with a marginal flange fitting over 10 the upper edge of the sleeve and providing an end bearing therefor. Formed integral with the cap member is a housing 10, arranged tangentially with respect to its periphery, said housing forming a bearing 15 and enclosure for a worm 11 and worm shaft 12 extending from said housing. Cut in the upper edge of the sleeve 3 and extending around the same are segments of worm teeth 13 which mesh with the worm 11. The 20 worm shaft 12 terminates in a squared end 12^a adapted to take the socketed end of a removable shaft (not shown) which is attached when the jack is to be operated.

Obviously by rotating the worm shaft 12 25 the sleeve 3 is rotated through the toothed engagement of the worm 11 with the teeth 13, and that the rotation of the sleeve imparts a vertical movement to the shank 5 through the threaded connection therebetween, thus causing the latter to be extended 30 upwardly (or downwardly if the post is to be retracted) from the end of the relatively stationary pedestal 1, a distance substantially equal to the length of the unthreaded 35 portion of said shank. This is all a matter of practical mechanics and therefore needs no extensive explanation.

The shank 5, it will be observed, extends 40 from the upper end of the pedestal and by the cap member 9 when in fully lowered or retracted position. This extended end portion serves as a support or connection for that part of the device having intimate contact or connection with the vehicle. These 45 parts will now be described. Mounted directly upon the end portion of the column 5 is a collar 15 open at its lower end and provided in its upper end with a rectangular opening 15^a. The connection is made between the collar and the end of the shank 5, 50 by means of bolts 16, 16. The portion of the collar immediately above the bolts is of increased thickness and forms a cavity 17 of reduced diameter as well as an internal 55 downwardly facing shoulder which bears upon the upper end of the shank at diametrically opposed points, as at 18, 18.

Mounted in the collar and connected therewith is the vehicle engaging member 60 19 of the jack having the form of a hook with a lateral or side opening, and resembling the letter C. At the base of the hook member 19 is an integral stud 20, for the most part cylindric in form, but having just 65 beneath a shallow boss 21 on the under side

of the hook member, a squared portion 22 forming a key, which is adapted to fit within the rectangular opening 15^a in the collar 15. Surrounding the stud below the key 22 is a coiled spring 23 held in place by a washer 24 secured by a screw 25 to the end of the stud.

The hook member proper 19 is designed and dimensioned so as to accommodate the spring or axle of the automobile and to sustain the load to be supported thereby. As is clearly shown in Figure 2, the hook member is tapered from top to bottom, providing the more rugged construction throughout the lower portions, as well as a wider bearing surface along the lower horizontal branch. Moreover, the inner portions of the several branches of the hook member are beveled, approaching a V-section throughout the vertical and upper horizontal branches. The extremity of the upper branch is turned downwardly at 26 in a rounded end and at the extremity of the lower branch a lug 27 is formed, thereby restricting the opening slightly, but affording a stop to prevent the part engaged within the hook from slipping or sliding outwardly through the opening.

It is further desirable to provide a roller 28 journalled in a recess formed in the under side of the upper horizontal branch of the hook member 19, as clearly shown in Figure 1. This may be a roller of relatively small diameter and extended substantially the length of the bearing surface, or several shorter rollers. The purpose of such a roller 30 is to facilitate the movement of the jack along the spring or axle in placing in the ultimate lifting position and to permit it to ride over obstructions, such as rivet heads and the like, that may project from the top 35 surface thereof.

As already suggested, the weight of the vehicle is supported upon the lower horizontal branch of the hook member in the actual 40 lifting, although the entire member is utilized in the application of the jack, as will now be described. Assuming that one of the rear wheels of the vehicle is to be raised from the ground, the jack in its retracted position is applied to the axle or the spring by hooking the hook member over the selected part and allowing the remaining part to swing 45 down into vertical position. Obviously, it is not necessary that the base of the jack be first placed in proper position for lifting, since the hooked engagement holds the jack suspended until it is sufficiently extended to bring the foot of the same into contact with the ground, whereupon the continued 50 extension of the jack seats it firmly in place and the weight brought upon the lower branch of the hook member. Nor is it always necessary to apply the jack at the exact 55 position where the lifting power is to be applied. For instance, the hooked end may 60

be hooked over the lower part of the spring near its outer end (assuming the springs are either full or three-quarters elliptical) and the jack will slide, or is easily guided, along the 5 spring to the desired position beneath the vehicle and near the axle. It is for this purpose that the roller 28 is utilized. In this manner the placing of the jack is accomplished without the inconvenience of crawling 10 beneath the vehicle.

This method of applying a jack is quite the reverse of that practiced with the ordinary device inasmuch as the jack is extended from the vehicle down to the ground instead of from the ground up to the vehicle. 15

Manifestly the method of applying the jack depends on the construction of the vehicle, the point selected for its application, and the part of the vehicle to be raised. For 20 this reason the hooked end 19 is adjustable about the vertical axis so that the opening of the hooked member may be faced in the desired direction with respect to the member to be engaged and the direction which the 25 worm shaft 12 will extend for the purpose of applying the operating shaft. By the swivel connection between the hook member 19 and the collar it is thus possible to pull the hook member axially with respect to the 30 remaining parts of the jack, thus releasing the key 22 from its square seat 15^a. This allows the hook member to be turned into any one of four positions ninety degrees apart, and then allowing the spring to draw 35 the same back into normal position with the key in locking position.

A further feature of construction is the provision of a joint or hinge at the junction of the lower and vertical branches of 40 the C-shaped member 19. As a preferable method of forming the hinge, the closed end of the lower branch is provided with a forked or slotted portion 30 adapted to receive a centrally disposed lug 31, integral 45 with the hinged portion. This lug conforms to the shape of the slot 30, which is extended laterally to provide an offset to take a hinge pin 32. The hinged parts are designed to have bearing contact along shoulders at 50 33, as well as along diagonal faces 34 at the lower edge of the lug 31 and at the bottom of the slotted portion 30. Spaced inwardly from the hinge pin 32 and on a line with the lower edge of the lug 31, are provided 55 registering holes adapted to receive a removable locking pin 35 for securing the hinged parts together in normal position. A chain 36 connects the pin 35 with a fixed pin 37 anchored in the lower branch of the hook member to secure the locking pin against loss. Thus, by removing the pin 35 the upper portion of the hook member can be 60 swung down and to one side as shown in dotted lines in Figure 1, allowing the jack to be used in the ordinary way.

The several features herein disclosed, and productive of the advantages claimed therefor, are combined in a readily portable, compact, efficient, and useful device, designed primarily to simplify and expedite the operations ordinarily requiring the use of lifting means, and, while I have disclosed a preferred embodiment of the invention, it is understood that I do not wish to be limited to the specific construction herein shown and 70 described except in so far as set forth in the appended claims:

I claim:

1. A lifting jack comprising a relatively stationary pedestal, an extensible shank having a laterally opening hooked shaped end portion capable of rotative adjustment about the axis of said shank and means for locking said end portion in one of several positions of rotatable adjustment. 80

2. A lifting device comprising a relatively stationary pedestal, an extensible shank mounted on said pedestal, a hook shaped end portion having swivel connection with said shank, said shank and hooked portions being 90 provided with interlocking members, and yieldable means acting to hold said members in locking engagement.

3. A lifting device comprising a pedestal, an extensible shank, means for manually extending and retracting said shank, a C-shaped portion mounted at the end of said shank through the medium of a stud and socket connection arranged to permit the swivelling of said portion, said stud having 95 a key adapted to normally engage a complementary seat in said recess, and to be withdrawn therefrom to permit the adjustment of said portion, and yieldable means acting to resist the withdrawal of said key 100 from its seat.

4. A lifting device comprising a pedestal, an extensible shank, means for manually extending and retracting said shank, a C-shaped portion mounted at the end of said 110 shank and provided with a stud adapted to engage a socket in the end of said shank, said stud and socket having an interlocking key and seat, and a yieldable member acting to resist the withdrawal of said squared portion 115 from its seat.

5. A lifting device comprising a pedestal, an extensible shank, means for manually extending and retracting said shank, a C-shaped portion mounted at the end of said shank, said portion having an axially disposed stud extending into a socket in the 120 end of said shank, and a spring within said socket acting to resist the withdrawal of said stud, said stud and recess being provided with an interfitting key and seat normally acting to lock said portion from rotation upon said shank. 125

6. A lifting device comprising a pedestal, an extensible shank operatively connected 130

with said pedestal, actuating mechanism for extending said shank axially of said pedestal and a laterally opening hook shaped member mounted at the end of said shank and capable of limited axial displacement relative to said shank, said member in one position of displacement being rotative into a plurality of positions of adjustment and in another position to be locked to said shank and 10 against rotation.

7. A lifting device comprising a pedestal consisting of a post provided with a foot plate, a rotative sleeve surrounding said post, a shank extending axially of said post and 15 having screw threaded connection with said sleeve, a worm and worm shaft mounted at the upper end of said pedestal and engaging teeth on said sleeve, and a hook-shaped object-engaging member mounted in swivel 20 connection at the end of said shank.

8. A lifting device comprising a pedestal consisting of a post provided with a foot plate, a rotative sleeve surrounding said post, a shank extending axially of said post and 25 having screw threaded connection with said sleeve, a worm and worm shaft mounted at the upper end of said pedestal and engaging teeth on said sleeve, and a C-shaped member mounted at the end of said shank and 30 having swivel connection therewith, and coacting locking members for normally locking said member to said shank and against relative rotative movement.

9. A lifting device comprising a pedestal 35 consisting of a post provided with a foot plate, a rotative sleeve surrounding said post, a shank extending axially of said post and having screw threaded connection with

said sleeve, a worm and worm shaft mounted at the upper end of said pedestal and engaging teeth formed in said sleeve, a cap member mounted at the end of said shank and having a socket formed therein, a C-shaped object-engaging member mounted at the end of said shank and having an axially 45 disposed stud extending into said socket, and means permitting said C-shaped member to be displaced axially and rotated, and means for locking said member in predetermined 50 positions of rotation.

10. A lifting device comprising a pedestal and an extensible shank having a hooked end portion consisting of two hinged together parts, whereby the upper portion of said end portion may be swung into inoperative 55 position.

11. A lifting device comprising a pedestal, an extensible shank, a C-shaped member at the end of said shank having a hinge at the junction of the lower and vertical branches 60 thereof, whereby the upper portion may be swung into inoperative position, and means for locking the hinged part in operative position.

12. A lifting device comprising a lower 65 branch forming a horizontal supporting surface and vertical and upper branch portion hinged to one end of said lower branch, and a locking pin, for normally securing said parts in C-shape and permitting the upper 70 portion thereof to be swung out of operative position.

In witness whereof, I hereunto subscribe my name this 19th day of July, A. D., 1923.

WM. G. PANCOAST.
